UNITED STATES PATENT OFFICE.

HENRY R. MATHIAS, OF ATHENS, OHIO.

SLIDEWAY.

SPECIFICATION forming part of Letters Patent No. 376,671, dated January 17, 1888.

Application filed September 9, 1887. Serial No. 249,247. (No model.)

To all whom it may concern:

Be it known that I, HENRY R. MATHIAS, a citizen of the United States, and a resident of Athens, in the county of Athens and State of Ohio, have invented certain new and useful Improvements in Slideways; and I do hereby declare that the following is a full, clear, and exact description of the invention, which will enable others skilled in the art to which it applies to make and use the same, reference being had to the accompanying drawings, which form a part of this specification, and in which—

Figure 1 is a side view of my improved slideways, showing them attached in operative position to beams or uprights. Fig. 2 is a front view of one of the same removed from the beams or uprights. Fig. 3 is a longitudinal section on line *x* *x* in Fig. 2. Fig. 4 is a cross-section view taken on line *y* *y* in Fig. 2; and Fig. 5 is a perspective view of an excelsior cutting-machine, showing my improvement secured in operative position to the upright beams thereof.

Similar letters of reference denote corresponding parts in all the figures.

My invention has relation to slideways for engines or machinery, it being shown in Fig. 5 of the accompanying drawings, for convenience of illustration, in connection with an excelsior cutting-machine, and it has for its object to reduce friction between the fixed and movable parts to a minimum; and to this end it consists in the improved construction and combination of parts of the same, as will be hereinafter more fully set forth.

In the accompanying drawings, the letter A indicates the portions of beams or uprights to which my improved slideways B B are attached by bolts B' B'. Each of these slideways consists of a casting, C, having sides D and E, respectively. The side D is beveled upon its inner face, as shown at F, the object of which will be hereinafter fully described.

G represents ears projecting from and integral with the bottom of the casting, and H denotes bolts projecting from the said bottom and having screw-threaded ends.

Wooden blocks I having elongated apertures J are secured in the casting between the ears G, and the bolts H project through these apertures and have a long metallic strip, I', secured upon their ends, which is clamped against

the blocks by means of nuts K. An adjustable metallic strip, L, bears against the rear edges of the blocks and adjusts them in unison by means of set-screws N, projecting through apertures in the rear side of the casting.

The operation of my invention is as follows: When it is desired to adjust the blocks, the nuts K of bolts H are loosened and the adjustable strip forced forward by means of the set-screws, and at the same time the blocks are forced forward, being supported and guided by the projecting ears in the bottom of the casting, and thereby reducing the V-shaped space formed by the forward edge of the blocks and the beveled side of the casting, in which space the vertical moving object is guided. After the blocks have been in this manner adjusted to their desired position, they are again securely clamped by the clamping-strip I' in the manner hereinbefore described. It will be seen that by cutting these blocks so that the grain extends transversely across them they will not be as liable to wear as they would if cut so as to have the grain parallel with their lengths.

From the foregoing description, taken in connection with the accompanying drawings, the operation and advantages of my invention will be readily understood. It will be seen that as the blocks wear they may be easily and quickly adjusted, or may be easily replaced with new ones by removing the clamping-strip and the nuts.

Having thus described my invention, I claim and desire to secure by Letters Patent of the United States—

1. In a slideway, the combination of a flanged casting having one of the flanges thereof beveled upon its inner face, with wooden blocks secured in said casting, thereby forming substantially a V-shaped way.

2. In a slideway, the combination of a flanged casting having one of the flanges thereof beveled upon its inner face, with wooden blocks having the grain thereof extending transversely across them secured in said flanged casting, thereby forming substantially a V-shaped way.

3. In a slideway, the combination of a casting having one of its sides beveled and ears projecting from its bottom, with wooden blocks adjustably secured to said casting and having

the grain thereof extending transversely across them.

4. In a slideway, the combination of a casting having one of its sides beveled and ears projecting from its bottom, with wooden blocks clamped and adjustably secured to said casting and having the grain thereof extending transversely across them.

5. In a slideway, the combination of a casting having ears projecting from its bottom, with wooden blocks having the grain thereof extending transversely across them, and an adjustable metallic strip and set-screws.

6. In a slideway, the combination of a cast-

ing, substantially as described, and ears and bolts projecting from the bottom thereof, with adjustable blocks having the grain thereof extending transversely across them, and having elongated apertures, a clamping-strip, and nuts.

In testimony that I claim the foregoing as my own I have hereunto affixed my signature in presence of two witnesses.

HENRY R. MATHIAS.
